UNITED STATES PATENT OFFICE.

WILLIAM F. PARISH, OF MINNEAPOLIS, MINNESOTA.

ADJUSTABLE CUT-OFF.

SPECIFICATION forming part of Letters Patent No. 363,255, dated May 17, 1887.

Application filed February 21, 1887. Serial No. 228,311. (No model.)

To all whom it may concern:

Be it known that I, WILLIAM F. PARISH, of Minneapolis, in the county of Hennepin, State of Minnesota, have invented certain Improvements in Adjustable Cut-Offs for Engines, of which the following is a specification.

This invention relates to improvements in the adjusting mechanism of cut-off valves of steam-engines; and the objects I have in view are to provide a cheap, simple, strong, and durable mechanism by which the valve may be accurately adjusted to cut off the steam at any desired point in the stroke and indicate the point of the stroke at or near which the steam will be cut off. These objects I accomplish by means of the construction hereinafter described, and particularly pointed out in the claims.

In the drawings, Figure 1 is a side elevation of a portion of an engine bed-frame and cylinder having my improved device applied thereto. Fig. 2 is a horizontal section of a valve, with a plan view of my adjusting device on the stem of the cut-off valve. Fig. 3 is a side elevation, on a larger scale, of the adjusting device. Fig. 4 is a sectional end elevation of the same. Fig. 5 is a plan view of the same. Fig. 6 is a detail.

In the drawings, 2 represents a portion of the bed-frame of a steam-engine, and 3 a portion of the steam-chest. These parts may be of any suitable or preferred construction. The steam-chest is provided with a sliding valve, 7, that is operated by a rod, 9, in the usual way. The steam-chest is also provided with a rider or cut-off valve consisting of the two slides 11 and 13, one for each steam-port in the main valve. These slides are each connected to a rod, 15, which is provided with right and left hand threads 16 and 18, so that by turning the rod the slides 11 and 13 are moved toward or from each other, thereby varying the cut-off.

The cut-off valve is operated by means of an eccentric-rod, 17, and rocker-arm 18, in the usual way.

A wrist-head, 20, is secured to the rocker-arm, and is provided at one side with a projecting arm, 21, which has an opening extending longitudinally into it, the arm being cut

away at each side to this opening, as shown in Figs. 3 and 4.

A revolving head, 23, is adapted to fit the opening in the arm 21, and is provided at one end with a hexagon, 25, and an annular shoulder, 26, that is adapted to bear against the end of the arm 21. The end of the revolving head is provided with a suitable opening, which is adapted to receive the end of the valve-stem 15, which is secured thereto by a pin, 27, or other suitable means. The opposite end of the head 23 is provided with a screw-thread, 28, as shown in Fig. 6.

A sleeve, 29, is provided with an external screw-thread and with an internal thread 65 adapted to fit the thread 28 on the head 23. This sleeve may, however, be secured to the head by any suitable means.

A slide, 30, is arranged in ways 31 on the face of the arm 21, and is provided with an in-turned end, 32, having sections of screw-threads that engage the threads on the sleeve 29. This slide is provided with a slot, 33, in the direction of its length, through which a clamping-screw, 34, passes. By means of this screw the slide may be clamped and locked in any desired position. The slide is provided with a suitable pointer, 36, and a scale is marked on the face of the arm 21, along which the pointer is moved as the valve is adjusted. 80 The pointer may be omitted, if preferred, and a mark may be made on the slide to serve the same purpose.

In putting the device together the slide 30 may first be put in place and secured by the screw 34. The sleeve 29 may then be inserted through the opening in the opposite side of the arm 21 and its threads be made to engage with the sectional threads on the inturned portion of the slide. The revolving head 23 is then inserted through the opening in the end of the arm and screwed into the sleeve 29. After this head is brought to the proper position a pin, 35, may be passed through the sleeve and the head, thus permanently securing these parts together. If preferred, the threads on the head 23 and the internal thread in the sleeve may be omitted and the sleeve secured by a pin or other device. The end of the valve-stem 15 is then secured to the end of 100

the head. The head 23 and sleeve 29 may first be put in position, and then the slide 30 may be put in place and its threaded end be entered upon the threads of the sleeve 29.

- 5 By applying a wrench to the hexagon on the head 23 and turning the same the valve-stem 15 will also be turned and the cut-off valve will be adjusted. The slide 30 will be moved by the threads on the sleeve 29 engaging the threads on the inturned end of the slide, and the position of the pointer on the scale will indicate substantially the point in the stroke at which the steam will be cut off. For instance, for a fifteen-inch cylinder the scale 15 may be marked $3\frac{1}{4}$, $7\frac{1}{2}$, $11\frac{1}{4}$, to indicate a cut-off at one-quarter, one-half, or three-quarters stroke, and the pointer may be brought opposite any division of the scale. Any other suitable marking for the scale may be used.
- 10 After the valve has been adjusted the slide may be clamped by the screw 34, and it will then be necessary to loosen this screw before the valve can be again adjusted, and it will be impossible for the adjustment to be accidentally changed. As the movement of the slide is limited by the screw 34, and as its movement limits the movement of the other parts, it will be impossible for an engineer or attendant to carelessly move the parts so as to 15 get them out of working position, except by first removing the clamping-screw and disengaging the slide from the threaded sleeve.
- 20
- 25
- 30

This adjusting device can be applied to any positive-movement cut-off valve, whether a rocker-arm is used for moving it or not, and either to a valve having two slides, such as shown, or to a valve having a single slide.

The scale may be on the slide and the pointer on the arm 21, if preferred.

I claim as my invention—

1. The combination, with the valve-stem, of the adjusting and indicating mechanism, consisting of the arm 21, the revolving head 23, to which the valve-stem is connected, the threaded sleeve 29, secured to said head, and the slide 45 40 45 30, engaging said sleeve and operated thereby, substantially as described.

2. The combination, with the valve-stem, of the arm 21, the revolving head 23, connected with said stem, the threaded sleeve 29 on said head, the slide 30, engaging said sleeve, the indicating-scale, and the clamping-screw 34, all substantially as described. 50

3. The combination, with the valve stem, of the revolving head 23, the slide operated by 55 said head, and the indicating-scale, substantially as described.

In testimony whereof I have hereunto set my hand this 17th day of February, 1887.

WILLIAM F. PARISH.

In presence of—

A. C. PAUL,

R. H. SANFORD.
